United States Patent Office.

I. S. PIGOTT, OF CENTRAL STATION, WEST VIRGINIA.

Letters Patent No. 71,785, dated December 3, 1867.

IMPROVEMENT IN LOG-WAGONS.

The Schedule referred to in these Letters Patent and making part of the same.

TO ALL WHOM IT MAY CONCERN:

Be it known that I, I. S. PIGOTT, of Central Station, Doddridge county, West Virginia, have invented a new and useful Improvement in Log-Wagons; and I do hereby declare that the following is a full, clear, and exact description thereof, which will enable others skilled in the art to make and use the same, reference being had to the accompanying drawings, forming part of this specification.

This invention relates to an improved log-wagon, cart, or sled, and consists in an upright frame arranged on the axle-tree or roller of a common log-wagon or cart, or on the cross-piece of a sled.

A pair of dogs is hung from the cross-piece of the frame, the cart backed up to the log, and the frame turned down upon it, the dog-irons driven into the log, and the horses on being started draw up the frame and swing the log upon the carriage. In the accompanying drawings—

Figure 1 is a front view of my improved log-wagon.

Figure 2 is a vertical longitudinal section thereof at the line *x x*.

Similar letters of reference indicate corresponding parts.

A is the axle-tree of the log-wagon, or cross-piece of a sled. B, the upright frame, steadied by the straps or rods C, secured to the tongue or pole of the wagon D.

When it is required to load, back up the wagon against the log, and tip it up, as shown in fig. 2; fix the dogs in the log, and the dog-ring to any suitable attachment, *b*, prepared for it in the transverse portion of the frame, start the horses forward, pulling on the chain *E*, thereby drawing down the tongue *D*, raising the frame, and with it the log, which swings itself upon the wagon.

I claim as new, and desire to secure by Letters Patent—

The log-wagon, constructed as described, having the frame B upon the axle A, and provided with the dogs grasping the timber, all operating as described, whereby the depression of the tongue D raises the timber and places it upon the axle A, and within the frame B, as herein described, for the purpose specified.

The above specification of my invention, signed by me, this 9th day of March, 1867.

I. S. PIGOTT.
